J. H. MACDONALD,
 SKELETON INTERLOCKING REINFORCE BAND FOR FERROCONCRETE CONSTRUCTION,
 APPLICATION FILED MAR. 7, 1910.

964,992.

Patented July 19, 1910.

UNITED STATES PATENT OFFICE.

JAMES H. MACDONALD, OF NEW HAVEN, CONNECTICUT.

SKELETON INTERLOCKING REINFORCE-BAND FOR FERROCONCRETE CONSTRUCTION.

964,992.

Specification of Letters Patent. Patented July 19, 1910.

Application filed March 7, 1910. Serial No. 547,903.

To all whom it may concern:

Be it known that I, JAMES H. MACDONALD, a citizen of the United States, residing at New Haven, in the county of New Haven 5 and State of Connecticut, have invented a new and useful Improvement in Skeleton Interlocking Reinforce-Bands for Ferro-concrete Construction; and I do hereby declare the following, when taken in connection with the accompanying drawings and 10 the numerals of reference marked thereon, to be a full, clear, and exact description of the same, and which said drawings constitute part of this specification, and represent, in—

Figure 1 a broken perspective view of skeleton, interlocking reinforce bands for ferro-concrete work, constructed in accordance with my invention. Fig. 2 a broken 20 view in side elevation of one of the longitudinal bands of my improved reinforce. Fig. 3 a corresponding view of one of the transverse bands of my improved reinforce. Fig. 4 a broken view in transverse section 25 of a sample of concrete work reinforced in accordance with my invention.

My invention relates to an improved form of metal reinforce for ferro-concrete construction, the object being to produce at a 30 low cost for manufacture, a reinforce of superior strength and efficiency, in the form of sheet-metal bands for use in the construction of concrete roadways and pavements, and in kindred situations.

With these ends in view my invention consists in skeleton, interlocking sheet-metal reinforce bands having certain details of construction as will be hereinafter described and pointed out in the claim.

In carrying out my invention as herein shown, I employ a plurality of vertically arranged longitudinal bands 2 made of sheet-metal and limited in length only by such practical considerations as the length of 45 the blanks from which the bands are made, weight and convenience of handling, etc. The said bands 2 are skeletonized, as it were, by the formation in them at regular intervals on a line well below their upper 50 edges of relatively large inverted truncated openings 3 and of triangular openings 4 located under the opposite ends of the openings 3 and made by removing portions of the lower edges of the bands. The said openings 3 and 4 result in the production of 55 regularly spaced vertical supports 5, in-

clined braces or struts 6, and bases 7 into which latter the lower ends of the braces or struts 6 merge and which constitute regularly spaced points of support between the 60 vertical supports 5. It will be understood, of course, that the concrete 8 in its fluid or semi-fluid state flows transversely through the openings 3 and 4, which thus insure the continuity and all-pervading character of 65 the concrete. The upper edges of the bands 2 are unbroken except for upwardly opening interlocking slots 9 arranged in line with the axes of the vertical supports 5.

With the longitudinal bands 2, I employ 70 a plurality of vertically arranged corresponding transverse bands 10 made of sheet metal and limited in length only by the width of the road-bed or side walk or other construction of whatever character in which 75 my improved reinforce may be used. The said bands 10 are skeletonized in precisely the same manner as the bands 2 by being cut away to form openings 3 and 4, vertical supports 5, struts or braces 6 and bases 7. 80 The bands 10 are also formed with downwardly opening interlocking slots 11 longer than the slots 9 in the bands 2 and permitting the longitudinal bands 2 and transverse bands 10 to be interlocked at right angles 85 with each other so as to produce rectangular inclosures or cells 12, having, as it were, pierced side walls for the concrete 8 which is laterally tied together, as it were, by its passage through the openings 3 and 4 in the 90 bands. As shown in Fig. 4, the vertical supports 5 and bases 7 representing the lower edges of the bands, rest upon a suitable bed 13 prepared to receive them, while above the upper edges of the bands is a top dressing 95 14 also of concrete and serving as a wearing surface.

It will be seen by reference to Fig. 1, that when the bands are interlocked the vertical supports of the longitudinal bands 2 100 will be combined with the vertical supports of the transverse bands 10 so as to form, as it were, a post having four flanges and supported by four inclined braces or struts, whereby great strength is secured. The interlocking of the bands as shown by Fig. 1 105 results in the production of a fabric, if I may use the term, coextensive with the area to be concreted and consisting, as it were, of a series of rectangular cells or inclosures 110 communicating with each other through their pierced side walls and all filled with

concrete which is continuous throughout the entire fabric by reason of its passage through the openings formed by piercing the bands.

5 My improved reinforce bands interlocked with each other and embedded in the concrete greatly reinforce the same. I may add that I am using the term "concrete" in its broadest sense and with the intention of covering all of the various compositions of a plastic character which are used in constructing roadways, side walks and the like.

10 I am aware that in the construction of asphalt pavements intersecting bands having their upper and lower edges respectively slotted to permit them to be interlocked, have been employed. I am also aware that 15 perforated bands having their upper and lower edges slotted to adapt them to be interlocked have been employed in the construction of frames for building blocks or 20 paving tiles, the cells formed by the intersection of the bands being designed to receive hydraulic cement or other material 25 which flows from one cell to the other before it hardens, through the perforations in the bands. I do not, therefore, broadly claim 30 interlocking slotted bands for asphalt construction, nor interlocking slotted bands having perforations for paving construction, but only my particular construction of interlocking bands designed to be entirely embedded in concrete and skeletonized so as to have the support of the lower edges of

the bands focused in part upon vertical supports which are themselves supported by trusses extending in four directions. 35

I claim:—

A sheet metal fabric for reinforcing concrete in which it is entirely embedded, the 40 said fabric consisting of sheet metal bands arranged at right angles to each other and respectively having their upper and lower edges formed with registering slots interlocked to form rectangular cells or inclosures for the reception of concrete, and the 45 said bands being skeletonized by the formation in them at regularly spaced intervals of inverted truncated openings separated by vertical supports containing the said slots 50 and having their lower ends flanked by triangular openings extending under the said truncated openings and cutting portions of the lower edges of the bands away, whereby 55 the two-part vertical supports located at the intersection of the bands when interlocked are virtually supported by four inclined braces or struts extending in opposite directions and formed by the lower side walls of the said inverted truncated openings. 60

In testimony whereof, I have signed this specification in the presence of two subscribing witnesses.

JAMES H. MacDONALD.
